Specification for Design.

Patented Nov. 8, 1921.

Application filed August 23, 1920. Serial No. 405,524. Term of patent 3½ years.

To all whom it may concern:

Be it known that I, ROLAND T. HUGHES, a citizen of the United States, residing in the village of Oak Park, in the county of Cook and State of Illinois, have invented a new, original, and ornamental Design for a Lighting-Fixture, of which the following is a specification, reference being had to the accompanying drawing, forming part thereof.

The drawing is a detail of a lighting fixture in a laurel wreath design, having special design cast tassel lights for ball lamps in a new position, in connection with a suspended semi-indirect glass bowl and top metal reflector.

I claim:

The ornamental design for a lighting fixture, as shown.

ROLAND T. HUGHES.
